UNITED STATES PATENT OFFICE.

JOHN MIDGLEY AND WILLIAM HALL, OF PAWTUCKET, RHODE ISLAND,
ASSIGNORS OF ONE-HALF TO WILLIAM F. SAYLES AND FREDERIC
C. SAYLES, BOTH OF SAME PLACE.

STOP-MOTION FOR WOOL-COMBING MACHINES.

SPECIFICATION forming part of Letters Patent No. 319,929, dated June 16, 1885.

Application filed February 25, 1884. (No model.)

To all whom it may concern.

Be it known that we, JOHN MIDGLEY and WILLIAM HALL, subjects of the Queen of Great Britain, residing at Pawtucket, in the county 5 of Providence and State of Rhode Island, have jointly invented a new and useful Improvement in Stop-Motions for Combing-Machines; and we do hereby declare that the following specification, taken in connection with the accompanying drawings, forming a part of the same, is a full, clear, and exact description thereof.

This invention relates to a stop-motion for machines for combing fibrous materials; and it consists in certain features of construction 15 which will be hereinafter fully described, and set forth in the claims.

Referring to the drawings, Figure 1 represents a plan of a combing-machine embodying the invention. Fig. 2 shows a front view of 20 the same. Figs. 3 and 4 show, respectively, a plan and an elevation of the stop-motion mechanism on a larger scale. Figs. 5 and 6 show, respectively, a plan and an elevation of a portion of the stop-motion having a modified form 25 of lever.

A represents the main annular comb, and B B' the small annular combs, of a combing-machine, all of which are revolved in the direction of the arrows by suitable gearing 30 driven from the shaft *a* in a manner well known to persons familiar with such machinery. The sliver *b*, which is the product of the machine, is obtained from these combs in the usual and well-known manner, and in the machine illustrated is delivered by the rolls C c to the trumpet D, which trumpet twists the sliver and delivers it to rolls E E, which discharge it from the machine. The roll C is mounted on a shaft, C', and, as shown in Fig. 2, is driven 35 from the shaft *a* by the bevel-gears 1 and 2, the shaft 3, and the gears 4, 5, 6, 7, and 8, the latter gear being attached to the shaft C'. The trumpet D is revolved by a belt, 9, passing over a pulley, 10, on the shaft *a*. The rolls 40 E E are driven from the shaft *a* by suitable gearing or in any preferred manner.

The stop-motion is intended to operate should the sliver *b* lack the requisite weight

by reason of a proper amount of material not being supplied to it, should said sliver become attenuated from any cause, or should it break, and, also, should the trumpet D become choked, so as not properly to take up the sliver delivered by the rolls C c, or should the rolls E E fail properly to draw the sliver through the trumpet.

As shown in all the figures of the drawings, a trough, F, underlies and bears against the sliver *b* between the rolls C c and the trumpet D. This trough is pivoted on the short arm 40 of a lever, f, which is pivoted to a bracket, g, secured to one of the standards G of the discharge-rolls E. To the long arm of said lever is attached a chain or cord, H, upon the lower end of which a clutch member, K, is suspended. As shown in Figs. 2 and 4, this clutch member is mounted on a stud, L, and has a clutch-face, k, which is intended to cooperate when allowed to do so with a clutch-face, m, on the hub of a fellow clutch member, M, also mounted on said stud. By means of a belt, N, the fellow clutch member M is constantly driven by a pulley, n, on the shaft C', or it may be driven from any other convenient source.

Secured to the periphery of clutch member K is a second chain or cord, P, which passes under a pulley, p, thence upward over a pulley, p', and is secured to an arm, q, on the shippings-rod Q, which is provided with the usual 50 fork, a', for engaging the driving-belt A'. In all the figures of the drawings this belt is shown in full lines on the driving-pulley.

Under normal conditions the sliver *b* will support the clutch member K, so that its 55 clutch-face *k* will be out of engagement with the clutch-face *m* on the hub of the fellow clutch member M. When, however, from any of the causes above enumerated, the stop-motion should operate the trough F will rise, 60 and the clutch member K will descend into engagement with the clutch-face *m*, as shown by dotted lines in Fig. 4, and will be rotated by the revolving pulley M. The rotation of the clutch member K will wind the chain P 65 around said clutch member, and thereby draw

the shipping-rod Q to the right, as shown by dotted lines, and cause the driving-belt to be shipped to the loose pulley A², thereby causing the machine to stop.

5 When the belt is to be shipped to the driving-pulley to start the machine, it will be necessary, in order that the rod Q may be moved for such purpose, that the clutch member K be raised out of engagement with the clutch-face m so that the chain P can unwind from the clutch member K as the said rod is moved. The disengagement of the clutch member K from the clutch-face m may be effected by grasping the chain H and lifting the clutch member K 15 by hand. We prefer, however, to have this operation performed automatically, and have therefore provided a chain or cord, R, which is secured to the chain or cord P below the pulley p', as shown in Figs. 2 and 4, and passes 20 over pulleys r and r', and is secured to the long arm of the lever f. Normally the chain R is somewhat slack. When, however, the clutch member K descends into engagement with the clutch-face m, and the chain P is being wound around said clutch member K to ship the belt, as hereinbefore described, the slack of the chain R will be taken up by the said descent of the clutch member K and the movement of the chain P, and the said 25 chain P, through the chain R, will gradually raise the long arm of the lever f, upon which the clutch member K is suspended, until the clutch member K becomes disengaged from the clutch-face m, which is intended to 30 occur when the belt A' passes off the driving-pulley. The clutch member K will be restrained by the chains P and R in its elevated position until the shipping-rod Q is moved to transfer the belt to the driving-pulley. The 35 clutch member K being thus held out of engagement with the clutch-face m, the chain P can unwind from the clutch member K to allow the rod Q to be moved, and the sliver b, having been repaired, the said sliver will support 40 the clutch member K in said elevated position 45 when the chains P and R no longer perform that office.

Although we prefer to employ the trough F, in order that a long bearing may be obtained upon the sliver, and to pivot the trough to 50 the lever f so that said bearing may be maintained under slight movements of said lever, due to immaterial inequalities in the sliver, yet the pivoted trough may be dispensed with, and the short arm of the lever, in any preferred form, be brought into contact with the sliver, as for instance as shown in Figs. 5 and 6.

What we claim, and desire to secure by Letters Patent, is—

1. A stop-motion mechanism consisting of a pivoted lever arranged, as described, to bear against a passing sliver, a clutch member suspended upon said lever, a revolving fellow clutch member located in vertical alignment therewith, and a chain or its equivalent attached to the periphery of the first-mentioned clutch member and connected with the shipping-rod of the machine, whereby when the sliver breaks the two clutch members will be 70 brought into engagement, the chain will be wound around the periphery of the clutch-member to which it is attached, and the shipping-rod will be moved to transfer the belt, substantially as set forth.

2. A stop-motion mechanism consisting of a pivoted lever arranged, as described, to bear against a passing sliver, a clutch member suspended upon said lever, a revolving fellow clutch member located in vertical alignment 80 therewith, a chain or its equivalent attached to the periphery of the first-mentioned clutch member and connected with the shipping-rod of the machine, and a chain or its equivalent attached to the first-mentioned chain and to 85 the said pivoted lever, substantially as described, and for the purposes specified.

JOHN MIDGLEY.
WILLIAM HALL.
